(Cl. D41—1)

To all whom it may concern:

Be it known that I, Don R. Hill, a citizen of the United States, residing at Warren, in the county of Trumbull and the State of Ohio, have invented a new, original, and ornamental Design for a Combined Air Motor and Hydraulic Pump, of which the following is a specification, reference being had to the accompanying drawing, forming a part thereof.

Figure 1 is a side elevational view of a combined air motor and hydraulic pump, showing my new design.

Figure 2 is a perspective view on a reduced scale of the same, and

Figure 3 is a top plan view of the same.

I claim:

The ornamental design for a combined air motor and hydraulic pump, substantially as shown.

DON R. HILL.
